[57] CLAIM

The ornamental design for an eyeglass case, as shown.

DESCRIPTION

FIG. 1 is a perspective view of a first embodiment of an eyeglass case showing my new design;

FIG. 2 is a top plan view of the first embodiment thereof;

FIG. 3 is a bottom plan view of the first embodiment thereof;

FIG. 4 is a front elevational view of the first embodiment thereof;

FIG. 5 is a rear elevational view of the first embodiment thereof;

FIG. 6 is a left side elevational view of the first embodiment thereof;

FIG. 7 is a right side elevational view of the first embodiment thereof;

FIG. 8 is perspective view of a second embodiment of an eyeglass case showing my new design;

FIG. 9 is a top plan view of the second embodiment thereof;

FIG. 10 is a bottom plan view of the second embodiment thereof;

FIG. 11 is a front elevational view of the second embodiment thereof;

FIG. 12 is a rear elevational view of the second embodiment thereof;

FIG. 13 is a left side elevational view of the second embodiment thereof; and,

FIG. 14 is a right side elevational view of the second embodiment thereof.
